ABSTRACT

A machine for uncoiling and straightening strip stock having a strip stock uncoiler means and an adjustable strip stock peeler means positioned adjacent the uncoiler means for stripping the leading edge of a coil of strip stock away from the body of the coil when the strip stock uncoiler means is actuated. A strip stock threading means is positioned adjacent the uncoiler means for receiving the leading edge of the strip stock coil from the peeler means and imparting to the strip stock a partial removal of the set that has been placed in the strip stock due to its winding into a coil. The threading means feeds the strip stock upwardly through an upper arcuate threading chute which then feeds the strip stock downwardly into a straightening means. A lower arcuate threading chute feeds the strip stock from the straightening means down and under the strip stock uncoiler means and thence to a strip stock processing machine without developing a set in the straightened strip stock.

STRIP STOCK UNCOILER AND STRAIGHTENING DEVICE

BACKGROUND OF THE INVENTION

1. Field of the Invention

This invention relates generally to strip stock handling apparatuses and, more particularly, to a machine for uncoiling and straightening strip stock and feeding the strip stock to a strip stock processing machine, such as a stamping machine, a press, or the like.

2. Description of the Prior Art

Strip stock handling apparatuses for uncoiling, straightening and feeding strip stock to a strip stock processing machine are well known in the art. One example of such prior art apparatuses is disclosed in the patent to Alvin F. Groll, U.S. Pat. No. 3,343,393 which discloses a strip stock handling apparatus that employs a conventional straightening mechanism positioned closely adjacent the coil from which the strip stock is drawn and oriented so that the straightened strip stock issues therefrom vertically. The strip stock is carried from the straightener over a series of supports and through a turn of 180° and then suspended on its own tension as a free loop between the supports at the end of that turn and guide mechanisms for introducing the strip stock into a strip stock processing machine. A disadvantage of the aforementioned prior art strip stock uncoiling and straightening apparatus is that with the straightener positioned adjacent to the coil from which the strip stock is drawn, a radius sufficient to avoid developing a set in the straightened strip stock must be maintained as the straightened strip stock proceeds vertically upward and thence in an arcuate path across the coil and then downward and under the coil to a strip stock processing machine. A further disadvantage of the aforementioned prior art strip stock handling apparatus is that the peeler apparatus for peeling the leading edge of the coil away from the body of the coil is not adjustable relative to the most advantageous position for stripping the leading edge away from the coil. Another disadvantage of the aforementioned prior art strip stock handling apparatus is that its loop storage capability is limited.

SUMMARY OF THE INVENTION

The present invention relates to a strip stock handling apparatus for uncoiling, straightening and feeding strip stock to a strip stock processing or utilizing machine.

It is an important object of the present invention to provide an improved strip stock uncoiling, straightening and feeding machine which overcomes the aforementioned disadvantages of the prior art strip stock uncoiling, straightening and feeding apparatuses.

It is another object of the present invention to provide a strip stock uncoiling and straightening machine which is adapted to uncoil strip stock from an uncoiler means and feed it upwardly, and thence over the uncoiler means, and thence downwardly through a strip stock straightener means, and thence under the uncoiler means to a strip stock processing machine without having to be concerned about the radius of the strip stock as it passes upwardly from the uncoiler means and over and around to the straightener means.

It is still another object of the present invention to provide a strip stock uncoiling and straightening

machine which is constructed and arranged to provide for an ample and optimum loop storage capability for feeding lengths not achievable by the aforementioned prior art apparatuses.

It is still another object of the present invention to provide a machine for uncoiling and straightening strip stock which is provided with a strip stock uncoiler means and an adjustable strip stock peeler means positioned adjacent the uncoiler means for stripping the leading edge of a coil of strip stock away from the body of the coil when the strip stock uncoiler means is actuated. A strip stock threading means is positioned adjacent the uncoiler means for receiving the leading edge of a strip stock coil from the peeler means and imparting to the strip stock a partial removal of the set that has been placed in the strip stock due to its winding into a coil. The threading means feeds the strip stock upwardly through an arcuate threading chute which thence feeds the strip stock downwardly into a straightening means. A lower arcuate threading chute feeds the strip stock from the straightening means down and under the strip stock uncoiler means and thence to the strip stock processing machine without developing a set in the straightened strip stock.

It is another object of the present invention to provide a machine for uncoiling and straightening strip stock which includes a power operated adjustable strip stock peeler means positioned adjacent the front of an uncoiler means for stripping the leading edge of the coil of strip stock away from the body of the coil when the strip stock uncoiler means is actuated, and a power driven strip stock threading means positioned adjacent the strip stock uncoiler means for receiving the leading edge of the strip stock coil from the strip stock peeler means and imparting to the strip stock a partial removal of the set that has been placed in the strip stock due to its winding into a coil.

It is still another object of the present invention to provide a machine for uncoiling and straightening strip stock which includes an uncoiler means, and a strip stock peeler means and a strip stock threading means positioned adjacent the strip stock uncoiler means for receiving the leading edge of the strip stock coil from said strip stock peeler means, and wherein the peeler means and the threading means are both operatively mounted on an adjustable support frame for adjusting the peeler means and the threading means relative to the uncoiler means. The strip stock threading means comprises a power driven first roll and a second idler roll adjustably mounted on an eccentric pivot means for moving said second roll toward and away from said first roll.

It is still a further object of the present invention to provide a machine for uncoiling and straightening strip stock which includes an uncoiler means, a strip stock peeler means and a strip stock threading means for feeding uncoiled strip stock upwardly through an upper arcuate chute that guides the strip stock upwardly and over the uncoiler means and thence downwardly into a strip stock straightener means from whence the straightened strip stock is fed downwardly over a lower arcuate threading chute for feeding the straightened strip stock to a strip stock processing machine, and wherein a portion of said lower threading chute is adapted to be moved to an open inoperative position to

permit a coil loading car to pass therethrough for loading a coil onto said uncoiler means. In one embodiment the portion of the lower threading chute that opens is carried on the coil loading car, and in another embodiment the portion of the lower threading chute that opens is a pair of power operated swingably mounted gates. In one embodiment the lower arcuate threading chute is disposed in a pit below the uncoiler means to provide an optimum loop storage capability for the machine. A combination hold-down roll and follower means is positioned adjacent the uncoiler means for operative engagement with a coil of strip stock as it is uncoiled.

Other objects, features and advantages of this invention will be apparent from the following detailed description, appended claims, and the accompanying drawings.

BRIEF DESCRIPTION OF THE DRAWINGS

FIG. 1 is a side elevational view of a first embodiment of a strip stock uncoiler and straightening machine made in accordance with the principles of the present invention.

FIG. 2 is a right hand elevational view of the structure illustrated in FIG. 1, taken along the line 2-2 thereof, and looking in the direction of the arrows.

FIG. 3 is a view similar to FIG. 2 but showing some of the parts removed and some of the parts moved to another position.

FIG. 4 is a fragmentary, enlarged, elevational section view of the structure illustrated in FIG. 1, taken along the line 4-4 thereof, and looking in the direction of the arrows.

FIG. 5 is a view similar to FIG. 4, but showing some parts in section, and with some parts removed.

FIG. 6 is a fragmentary, enlarged, elevational view of the combination coil peeling and threading means illustrated in FIG. 2.

FIG. 7 is a broken, fragmentary, partial section view of the structure illustrated in FIG. 6, taken substantially along the line 7-7 thereof, and looking in the direction of the arrows.

FIG. 8 is an enlarged, fragmentary, side elevational view of the strip stock straightener illustrated in FIG. 2.

FIG. 9 is a side elevational view of a second embodiment of the invention.

FIG. 10 is a top plan view of the structure illustrated in FIG. 9, taken along the line 10-10 thereof, and looking in the direction of the arrows.

FIG. 11 is a fragmentary, enlarged, side elevational view of the strip stock uncoiling means and combination coil peeling and threading means illustrated in FIG. 9.

FIG. 12 is a fragmentary, schematic, side elevational view of the second embodiment illustrated in FIG. 9, and showing a portion of the structure in an enlarged condition and with parts removed.

FIGS. 13 and 13a illustrate the double cone or double mandrel type of arbor employed in the strip stock uncoiler means employed in the second embodiment of FIG. 9.

FIG. 14 is a fragmentary, enlarged, side elevational view of the strip stock straightener employed in the second embodiment of FIG. 9.

FIG. 15 is an enlarged, fragmentary, elevational view of the swinging strip stock guide gate structure illustrated in FIG. 10, taken along the line 15-15 thereof, and looking in the direction of the arrows.

FIG. 16 is a fragmentary, horizontal sectional view of the structure illustrated in FIG. 15, taken along the line 16-16 thereof, and looking in the direction of the arrows.

10 DESCRIPTION OF THE PREFERRED EMBODIMENTS

Referring now to the drawings, and in particular to FIGS. 1 and 2, the numeral 10 generally designates a supporting surface, as a concrete floor, on which is operatively mounted a first illustrative embodiment of a machine for uncoiling, straightening, and feeding strip stock to a strip stock processing machine. In FIG. 1, the numeral 11 generally designates a conventional storage rack for storing a plurality of coils 12 of strip stock. The numeral 13 generally designates a supporting structure for operatively supporting a strip stock uncoiler means generally indicated by the numeral 15 and an upper arcuate threading chute which is generally indicated by the numeral 16.

The numeral 14 generally designates a coil loading car which is adapted to move a strip stock coil 12 from the storage rack 11 to a position for loading the coil 12 onto a conventional single end arbor generally indicated by the numeral 19. The numeral 20 generally designates a combination strip stock peeler means and threading means for feeding strip stock uncoiled from a coil 12 upwardly and through the upper arcuate threading chute 16 and into a conventional strip stock straightener, generally indicated by the numeral 17, which is disposed to the rear side of the uncoiler means 15. The straightened strip stock is then fed downwardly into a lower arcuate threading chute, generally indicated by the numeral 18, and thence to a strip stock processing machine. As shown in FIG. 2, the lower arcuate threading chute 18 extends downwardly and under the uncoiler means 15. As shown in FIG. 3, the numeral 21 generally designates a combination strip stock coil hold-down roll and follower means positioned adjacent the strip stock uncoiler means 15 for operative engagement with a coil 12 as it is uncoiled.

In FIG. 3 the numeral 12 designates the largest diameter coil which can be handled on the uncoiler means 15, and the numeral 12a indicates the smallest diameter coil. The numeral 12b shows the smallest diameter coil 12a moved into an operative position on the arbor 19. In FIG. 1 the numeral 14a shows the position of the loading car 14 when it is in a position to remove a coil 12 from the outer end of the storage rack 11.

As best seen in FIG. 5, the coil loading car 14 is rollably mounted on a pair of railroad tracks 22 which extend under the storage rack 11 and the uncoiler means 15 (FIG. 1). The coil loading car 14 is rollably mounted on the tracks 22 by a pair of front wheels 24 and a pair of rear wheels 26 which are operatively mounted on a front axle 23 and a rear axle 25, respectively.

The coil loading car 14 is driven along the tracks 22 by the following described drive means. As shown in FIG. 5 a pair of driven sprockets 27 are fixedly mounted by any suitable means on the rear shaft 25.

The sprockets 27 are driven by a pair of drive chains 30 which are mounted on a pair of drive sprockets 28. The drive sprockets 28 are fixedly mounted on the output shafts 29 of a gear reducer 31 which is operatively driven by a suitable electric motor 32, as for example a five-horsepower motor.

The numeral 14 in FIG. 1 designates the loading car in its normal storage position during the operation of the uncoiling and straightening machine of the present invention.

As shown in FIGS. 1 and 3, the coil loading car 14 is provided with a suitable hydraulic lift means 33 which comprises a suitable hydraulic cylinder and means for supplying hydraulic fluid under pressure to the cylinder. A suitable coil supporting cradle or bracket 34 is adjustably mounted on the cylinder rod of the hydraulic lift means 33. It will be understood that the hydraulic lift means 33 is utilized for centering coils 12 of various diameters on the arbor 19.

The numeral 35 in FIGS. 2 and 3 designates an inverted U shaped opening in the machine's supporting structure into which the coil loading car 14 and a coil 12 may pass for loading the coil onto the uncoiler means 15.

As illustrated in FIG. 2, the single end arbor 19 is expanded and retracted to satisfy varying coil inside diameters by a suitable driven sprocket and the drive chain 36 which is driven by a suitable electric motor 37. The motor 37 also drives a chain 38 which drives a sprocket 39 that is suitably geared to the arbor shaft to rotate the arbor for threading strip stock across the peeler point 71. It will be understood that the single end arbor 19 may be any suitably conventional arbor of this type.

As viewed in FIG. 2, the coil 12 is rotated in a clockwise direction so as to feed the strip stock 40 upwardly and to the left of the coil 12.

The hold-down means 21 includes a hold-down roll 41 which is adapted to abut the coil 12 adjacent the point on the coil where the strip stock leaves the coil. The hold-down roll 41 is rotatably mounted in a suitable manner on one end of a pair of carrier arms 42. The other ends of the carrier arms 42 are fixed on the front ends of a second pair of carrier arms 43 which have their rear ends fixed to a pair of carrier pivot arms 44. The pivot arms 44 are pivotally mounted on suitable shafts 45 which are secured to suitable brackets on the machine support structure. The aforescribed carrier arms 42, 43 and 44 form a hold-down roll carrier frame which is adapted to be swung about the pivot shafts 45 to move the hold-down roll 41 into operating engagement against the coil 12 by a pair of suitable fluid cylinders 46. The fluid cylinders 46 have their head ends pivoted on pivot shafts 47 which are supported by brackets 48 that are carried on the machine supporting structure. The cylinder rods 49 have their outer ends pivotally secured to the hold-down roll carrier frame by pivot shafts 50. An electric motor is on the hold-down roll frame and drives chain 52 which is threaded around a suitable sprocket attached to the hold-down roll 41 for driving the roll 41.

The fluid cylinders 46 are controlled so as to constantly bias the hold-down roll 41 against the coil 12 and provide a constant guiding action as the coil 12 diminishes in size.

As shown in FIG. 2, the combination stock peeler means and threading means 20 includes a supporting frame generally indicated by the numeral 53. As shown in FIG. 7, the supporting frame 53 includes a pair of spaced-apart elongated plates which have at their upper ends a pivot shaft 54 which are each suitably journaled in a pivot support member, as illustrated in FIG. 2. The support frame 53 is pivoted about the axis of the shafts 54 by a pair of fluid cylinders 57.

10 The outer ends of the cylinder rods 58 of the cylinders 57 are pivotally mounted by a pair of pivot pins 55 to the support frame 53, as illustrated in FIGS. 2 and 7. The head ends of the cylinders 57 are pivotally mounted by a pair of shafts 58 on suitable brackets as 59 which are carried on the upper arcuate threading chute 13, as shown in FIG. 2.

15 The upper arcuate threading chute 13 includes an arcuate, channel-shaped chute 60 which is supported on the top of the uncoiler means supporting structure by a plurality of radially disposed support posts 61 through 65. The channel-shaped chute 60 operably supports a plurality of arcuately shaped-apart strip stock support rolls 66 for supporting and carrying the strip stock 40 as it passes through the threading chute 13. The channel-shaped chute 60 is enclosed around its outer periphery by a suitable cover 68. As shown in FIG. 1, a strip stock guide means 69 is mounted at the discharge end of the threading chute 60. As shown in FIG. 2, a fixedly mounted entrance guide member 70 is disposed so as to guide the strip stock 40 into the channel-shaped chute 60.

20 As shown in FIGS. 2 and 7, the stock peeler means includes a peeler point 71. As shown in FIG. 7, the peeler point 71 is supported on a pair of spaced apart carrier arms 72 which are pivotally mounted at their upper ends on a pair of shafts 73. The shafts 73 are suitably journaled on the side members of the support frame 53. As illustrated in FIG. 6, each of the peeler point carrier arms 72 is operatively connected to a fluid cylinder 74 for moving the peeler point 71 toward and away from a coil 12 so as to engage the leading edge of a new coil 12 and guide it into the threading means. Each of the rod ends of the cylinders 74 is attached by means of a suitable pivot shaft as 76 to its respective carrier arm 72. The head ends of the cylinders 74 are pivotally mounted by suitable pivot shafts as 75 on the support frame 53.

25 30 35 40 45 50 55 60 65 The strip stock threading means includes a power driven roll 77 which is rotatably mounted by suitable bearings 78 on the side arms of the support frame 53. The roll 77 is provided with an end shaft 79 on which is fixed a driven sprocket 80. As shown in FIG. 3, the sprocket 80 is driven by a suitable drive chain 81 that is in turn driven by a sprocket member operatively mounted on a suitable electric drive motor 82 that is carried on the machine support structure. The strip stock threading means further includes the idler roll 83 (FIG. 7) which is rotatably mounted by a pair of support bearings 84 that are each mounted on one end of a pair of eccentric arms 85. The eccentric arms 85 are pivotally mounted on a pair of eccentric shafts 86 which are carried in an eccentric position on the inner ends of the shafts 73. The cylinder rod ends of a pair of fluid adjustment cylinders 87 are pivotally connected by a pair of pivot shafts 88 to the other ends of the two

eccentric arms 85. The head ends of the adjusting cylinders 87 are attached by suitable pivot shafts 89 to a pair of mounting brackets 90 that are secured to an upper arm 91 on the support frame 53. The side members of the support frame 53 are interconnected at their upper and lower ends by the cross arms 91 and 91a respectively.

The movable roll 83, because of its eccentric mounting relative to the power driven roll 77 which is fixed relative to the support frame 53, exerts a downward pressure and produces a tendency to wrap the strip stock about the roll 77. This last-mentioned action functions to partially remove the set that has been placed in the strip stock due to its winding into a coil. The movable roll 83 can be adjusted so as to approximate the set in the coil to the radius of the upper arcuate threading chute 13. FIG. 2 shows the movable roller 83 in the inoperative position and also in the operative position 83a adjacent the driven roll 77. FIG. 3 also shows the movable roll 83 in the inoperative position moved apart from the roll 77 to permit the leading edge of a new coil 12 to be guided between the rolls 77 and 83 by the puller point 71 and thence upwardly into the threading chute 16. The movable roller 83 exerts the aforementioned downward pressure and tendency to wrap the strip stock 40 about the roll 77 when the roll 83 is moved to the operative position shown in FIG. 2. When the movable roll 83 is moved from the inoperative position shown in FIG. 3 to the operative position shown by the numeral 83a in FIG. 2, it engages the strip stock 40 and moves it to the position 40a, shown in FIG. 2, against the roll 77 so as to produce said downward pressure and tendency to wrap the strip stock about the roll 77 and impart to the strip stock a partial removal of the set that was placed in the strip stock material due to its winding into a coil.

As shown in FIG. 2, the strip stock 40 is discharged from the upper arcuate threading chute 13 downwardly into a conventional straightener means 17. It will be understood that any suitable strip stock straightener mechanism may be employed. Accordingly, the straightener means 17 is only schematically illustrated and described.

As best seen in FIG. 8, the straightener means 17 includes an upper set of power driven pinch rolls 92 and 102 and a lower set of power driven pinch rolls 93 and 102. The fixed pinch rolls 92 and 93 are provided with power driven sprockets 95 which are driven by a chain 96 that is trained around an idler sprocket 94 and a drive sprocket 97 on the output shaft of a suitable speed reducer apparatus 98. As shown in FIG. 2, the speed reducer apparatus 98 is operatively connected by a suitable coupling 99 to the output shaft of a suitable electric drive motor 100.

The straightener means 17 further includes the fixed straightener rolls 101 which coact with the two movable straightener rolls 108 which are carried on a suitable structure that is adjustable by a conventional jacking means that is driven by suitable motors, and which is indicated generally by the numeral 109.

The movable pinch rolls 102 are operatively mounted on carrier arms 103 which each have one end pivotally mounted on a shaft 104. The carrier arms 103 are adapted to be pivoted around the shafts 104 so as to move the pinch rolls 102 toward and away from their

mating power-driven rolls 92 and 93. The carrier arms 103 are adapted to be moved about the pivot shafts 104 by a pair of fluid cylinders 106 which have their cylinder rod ends connected to the carrier arms 103 by the pivot shafts 105, and which have their head ends pivotally mounted to the machine supporting structure by a shaft 107.

As illustrated in FIG. 4, the movable portion 111 of the lower arcuate threading chute is carried by the loading car 14 and is secured thereto by any suitable means as by a plurality of angle bars 113. FIG. 1 shows the loading car 14 in the normal storage position whereby the movable chute portion 111 is in alignment with the fixed portions 110 and 112.

In use, the coil loading car 14 moves a coil 12 into position on the arbor 19. The stock peeler point 71 which is adjacent the uncoiler means 15 is then operated for stripping the leading edge of a coil of strip stock away from the body of the coil and to feed it in between the two rolls of the threading means. The threading means then feeds the strip stock upwardly and through the upper arcuate threading chute 13 and thence downwardly into the straightening means 17. The straightened strip stock then passes downwardly through the lower arcuate threading chute and to a strip stock processing machine. It will be seen that the eccentrically mounted roll 83 in the frame means functions with the driven roll 77 to impart to the strip stock a partial removal of the set that has been placed in the material due to its winding into a coil. With the adjustable eccentric mounting of the roll 83 and the overall adjustment means of the threading means, it is possible to approximate the set in the coil to the radius of the overhead arcuate chute 13. The prior art devices cannot accomplish this action and must be concerned with maintaining an upper arcuate path of a predetermined amount so that a set will not be put back into the material. The applicant's device is not concerned with such a problem since the upper arcuate threading chute path is determined before the strip stock material gets into the straightener means.

FIGS. 9 through 16 illustrate a second embodiment of a strip stock uncoiler and straightening machine made in accordance with the principles of the present invention. The apparatus illustrated in FIGS. 9 through 16 is constructed generally in the same manner and operates in the same manner as the aforescribed first embodiment of FIGS. 1 through 8. The main difference is that the arbor for holding the coil in the uncoiling means is a double cone arbor as compared to a single end arbor in the first embodiment. In this second embodiment the lower arcuate threading chute is disposed in a pit beneath the uncoiler means and a swinging gate means is provided to permit the loading car to pass through the threading chute to load a coil on the arbor means.

In the embodiment of FIGS. 9 through 16, the parts 60 of the structure which are identical or correspond to parts of the first embodiment, have been marked with the same reference numerals followed by the small letter *b*.

As shown in FIG. 9, a coil loading car 14b having a hydraulic lift means 33b, is adapted to be moved in the same manner as the loading car in the first described embodiment along rails 22b for moving a coil 12 from a

storage position to the uncoiler means 15b. The strip stock is uncoiled in the same manner as the first described embodiment and it is assisted by a combination peeler and threading means 20b for threading the same into the upper arcuate threading chute 13b. The strip stock is then passed downwardly through a conventional straightener means 17b which is similar to the straightener 17 of the first embodiment but is somewhat different in the drive means for the rolls. However, it will be understood that the straightener means 17b can be of any conventional type. The straightened strip stock 40b passes downwardly from the straightener 17b and over a pair of swinging gates 143 which permit the loading car 14b to move into the machine to insert a coil 12 on the uncoiler means 15b. After passage over the swinging gates 143, the straightened strip stock passes downwardly over the arcuate threading chute 120. It will be understood that the gates 143 function with the chute 120 to provide what may be defined as the lower arcuate threading chute. It will be seen that a portion of the lower arcuate threading chute is disposed in a pit 119 beneath the uncoiler means 15b. The provision of the pit 119 for housing a portion of the threading chute 120 permits a long loop storage capacity not heretofore possible with the prior art machines. The second embodiment is also adapted to handle wide and heavy coils.

As shown in FIGS. 13 and 13a, the double arbor employed in the second embodiment is a conventional apparatus and it is schematically shown to show the general operation. It will be understood that any suitable double arbor may be employed.

The illustrated double arbor includes the two opposed arbors 121 and 122. As shown in FIG. 13, the arbor 121 is rotatably mounted by its support shaft 123 on a pair of suitable bearings 125 in a supporting structure generally indicated by the numeral 124. The rear end of the shaft 123 is operatively connected by a suitable clutch means 128 to a driven sprocket 127. The sprocket 127 is driven by a chain 129 which is threaded over a suitable drive sprocket 130 on the output shaft 131 of a suitable drive motor and gear reduction means generally indicated by the numeral 132. The last mentioned structure describes the means for turning the arbor. As shown in FIG. 13a, the arbor 122 is rotatably mounted in a similar manner as indicated by the corresponding reference numerals followed by the small letter *a*. However, the arbor 122 is an idler arbor. The numeral 118 generally indicates a suitable fluid operated brake means for braking the arbor cone 121.

As shown in FIG. 13, the arbor 121 is adapted to be moved inwardly and outwardly for the following described structure. The arbor supporting structure 124 is slidably mounted on suitable ways on a base supporting structure 133. The arbor supporting structure 124 is provided with a depending nut 134 which is threadably mounted in the conventional manner on a conventional lead screw 135. The lead screw 135 is journaled in suitable bearings 136 and it is rotated by a driven sprocket 137. The sprocket 137 is driven by the chain 139 which in turn is driven by the drive sprocket 138 that is mounted on the output shaft 140 and a suitable gear reducer 141. A suitable electric motor 142 is operatively connected to the gear reducer 141. FIG. 13a illustrates the same structure for moving the

arbor cone 122 forwardly and backwardly and the same parts have been marked with the same reference numerals followed by the small letter *a*.

The straightener means 17b is substantially similar to the conventional straightener means 17 illustrated in the first embodiment. Accordingly, the similar parts in FIG. 14 have been marked with the same reference numeral followed by the small letter *b*. As schematically illustrated in FIG. 12, the drive rolls for the straightener are driven by the drive chain 96b from a suitable motor gear reducer source 98b and 100b as illustrated in FIG. 9. The drive is conveyed from the drive chain 96b to the various drive rolls by internal gearing in the straightener 17b in a conventional manner.

The swinging gate means 143 is illustrated in FIGS. 15 and 16. The gate means 143 comprises a pair of gates which include an outer vertical rail 144 and a plurality of vertically spaced apart horizontal fixed support members 146. A plurality of vertically extending rods 145 are fixed in spaced apart positions on the inner side of the horizontal support members 146. Each of the gate rails 144 are hingedly mounted by a pair of suitable hinge means generally indicated by the numeral 147. A pair of suitable fluid operated rotary actuator motors 148 are operatively connected to the upper hinge shafts which in turn are fixed to the gates.

It will be understood that any suitable control system may be used for operating the various aforescribed parts of the uncoiler and straightener machine of the present invention so as to synchronize the operation of each of the various parts, as desired.

While it will be apparent that the preferred embodiments of the invention herein disclosed are well calculated to fulfill the objects above stated, it will be appreciated that the invention is susceptible to modification, variation and change.

What we claim is:

1. In a machine for uncoiling and straightening strip stock, the combination comprising:
  - a strip stock uncoiler means mounted on a supporting structure for rotatably mounting a coil of strip stock on a horizontal axis;
  - an adjustable strip stock peeler means positioned adjacent the front of said strip stock uncoiler means for stripping the leading edge of the coil of strip stock away from the body of the coil when the strip stock uncoiler means is actuated;
  - a strip stock threading means positioned adjacent the strip stock uncoiler means for receiving the leading edge of the strip stock coil from said strip stock peeler means and imparting to the strip stock a partial removal of the set that has been placed in the strip stock due to its winding into a coil, and thence feeding the coil upwardly;
  - an upper arcuate threading chute positioned above said strip stock uncoiler means for receiving the uncoiled strip stock as it is fed upwardly from said strip stock threading means and for supporting and guiding the uncoiled strip stock upwardly and over the strip stock uncoiler means and thence downwardly behind the strip stock uncoiler means;
  - e. a strip stock straightener means positioned to receive the strip stock from said threading chute; and,

- f. a lower arcuate threading chute extending from said strip stock straightener means and beneath said strip stock uncoiler means for supporting and feeding the straightened strip stock to a strip stock processing station and being of a radius of curvature sufficient to prevent the developing of a set in the straightened strip stock. 5
2. A machine for uncoiling and straightening strip stock as defined in claim 1, including:
- a. a strip stock coil hold-down roll and follower means positioned adjacent said strip stock uncoiler means for operative engagement with a coil of strip stock as it is uncoiled. 10
3. A machine for uncoiling and straightening strip stock as defined in claim 2, wherein:
- a. said strip stock peeler means and strip stock threading means are carried on a common swingably mounted support frame. 15
4. A machine for uncoiling and straightening strip stock as defined in claim 3, wherein:
- a. said strip stock threading means comprises a power driven first roll operatively mounted on said support frame and an idler second roll adjustably mounted on an eccentric pivot means carried on said support frame for moving said second roll toward and away from said first roll. 20
5. A machine for uncoiling and straightening strip stock as defined in claim 3, wherein:
- a. said strip stock peeler means comprises a peeler point swingably mounted on said support frame; and, 30
- b. means for moving said peeler point toward and away from a strip stock coil on said uncoiler means for stripping engagement with the leading edge of the coil. 35
6. A machine for uncoiling and straightening strip stock as defined in claim 2, wherein said strip stock coil hold-down and follow means includes:
- a. a power driven roll swingably mounted adjacent said uncoiler means; and, 40
- b. power means for normally biasing said hold-down roll into operative engagement with a strip stock coil on said uncoiler means.
7. A machine for uncoiling and straightening strip stock as defined in claim 6, wherein:
- a. said power means comprises a hydraulic cylinder. 45
8. A machine for uncoiling and straightening strip stock as defined in claim 2, wherein:
- a. said supporting structure is positioned on a supporting surface; and, 50
- b. said lower arcuate threading chute extends between said strip stock uncoiler means and said supporting surface.
9. A machine for uncoiling and straightening strip stock as defined in claim 8, including:
- a. a power driven coil loading car rollably mounted to move a strip stock coil from a storage position adjacent the strip stock uncoiler means into a position for mounting on said strip stock uncoiler 55

- means.
10. A machine for uncoiling and straightening strip stock as defined in claim 9, wherein:
- a. said lower arcuate threading chute includes a movable portion disposed in a normal operative position beneath said uncoiler means and movable into an inoperative position when said coil loading car is moved to a position beneath said uncoiler means. 60
11. A machine for uncoiling and straightening strip stock as defined in claim 10, wherein:
- a. said lower threading chute movable portion is operatively carried by said coil loading car for movement between said operative and inoperative positions.
12. A machine for uncoiling and straightening strip stock as defined in claim 9, wherein:
- a. said strip stock uncoiler means includes a single end arbor for retaining a coil in operative position on said uncoiler means; and,
- b. said coil loading car is adapted to move a strip stock coil from a storage position to a position for loading the coil on said single end arbor. 65
13. A machine for uncoiling and straightening strip stock as defined in claim 2, wherein:
- a. said supporting structure is positioned on a supporting surface;
- b. a pit is formed in said supporting surface beneath said uncoiler means, and said pit extends beyond the front end of said supporting structure; and,
- c. said lower threading chute comprises a first portion extending downward from said straightening means and a second portion disposed in said pit. 70
14. A machine for uncoiling and straightening strip stock as defined in claim 13, including:
- a. a power driven coil loading car rollably mounted to move a strip stock coil from a storage position adjacent the strip stock uncoiler means into a position for mounting on said strip stock uncoiler means. 75
15. A machine for uncoiling and straightening strip stock as defined in claim 14, wherein:
- a. said lower threading chute first portion comprises a pair of swingably mounted gate members disposed in a normal closed operative position; and,
- b. a power means is operatively connected to each of said swingable gate members to move the same into an inoperative open position when said coil loading car is moved to a loading position at said uncoiler means. 80
16. A machine for uncoiling and straightening strip stock as defined in claim 14, wherein said strip stock uncoiler means includes:
- a. a double cone arbor for retaining a coil in operative position on said uncoiler means; and,
- b. said coil loading car is adapted to move a strip stock coil from a storage position to a position for loading the coil on said double cone arbor. 85
